(57) **CLAIM**

The ornamental design for a crusher feed hopper wear protection cassette, as shown and described.

DESCRIPTION

FIG. 1 is a perspective view of the crusher feed hopper wear protection cassette showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof; and

FIG. 7 is another side elevational view thereof.

FIG. 8 is a perspective view of another embodiment of the crusher feed hopper wear protection cassette showing our new design;

FIG. 9 is a top plan view thereof;

FIG. 10 is a bottom plan view thereof;

FIG. 11 is a front elevational view thereof;

FIG. 12 is a rear elevational view thereof;

FIG. 13 is a side elevational view thereof; and,

FIG. 14 is another side elevational view thereof.
